UNITED STATES PATENT OFFICE.

KENT KANE McENTYRE, OF CALHOUN, GEORGIA, ASSIGNOR OF ONE-HALF TO MURRAY L. UPSHAW, OF RYDAL, GEORGIA.

KNOCKDOWN CRATE.

Application filed March 19, 1924. Serial No. 700,277.

This invention relates to crates, and particularly to knock-down crates or boxes such as are used for poultry, vegetables, eggs, and a large number of other commodities.

5 The general object of the invention is to provide a very simple crate which, when folded, is extremely compact so that the return charges on the crate are very small and which, when expanded, constitutes a full sized crate 10 thoroughly braced for shipment, and in which the parts are locked in their expanded condition against any accidental tendency to "knock down."

15 A further object is to provide a construction of this character having corner posts for the ends and sides which are so arranged that when the crate or box is collapsed, the corner posts will move downward out of the way of each other, the end corner posts holding the 20 sides and the side corner posts locked or closed.

25 A still further object in this same connection is to provide a construction of this character wherein when the sides are lifted into vertical position and the ends are lifted into vertical position, the sides will hold the ends against collapse, means being provided for locking the sides in this vertical position.

Another object is to provide a construction 30 wherein the slats or equivalent elements are on the outside of the frame, thus making repair work particularly easy.

Still another object is to provide a device 35 of this character having relatively few pieces and this being much more easily constructed than most of the knock-down crates or boxes known to me.

A further object is to provide a construction 40 of this character wherein the hinges holding the corner posts in place are bolted to the relatively heavy bottom of the box or crate so that this hinged connection of the post to the bottom will withstand rough usage.

45 Other objects will appear in the course of the following description.

My invention is illustrated in the accompanying drawings, wherein:—

Figure 1 is a longitudinal vertical sectional view through a crate constructed in accordance with my invention;

Figure 2 is a section on the line 2—2 of Figure 1;

Figure 3 is a section on the line 3—3 of 55 Figure 1;

Figure 4 is a fragmentary bottom plan view of one corner of the crate;

Figure 5 is a top plan view of the bottom portion of the crate partially collapsed;

Figure 6 is a longitudinal sectional view 60 through the construction shown in Figure 5, but showing the crate fully collapsed with the cover in place thereon;

Figure 7 is a section on the line 7—7 of Figure 6.

Referring to these drawings, it will be seen that my improved crate comprises a bottom board 10 which has a width equal to the extreme width of the crate and a length somewhat greater than the body of the crate. This 70 bottom is preferably solid, though not necessarily so, and at its end carries two transversely extending cleats 11 projecting up from the upper face of the bottom.

Hinged to the bottom at each end of each 75 cleat 11 is a vertical corner post 12, the two corner posts 12 at each end of the bottom carrying transverse slats 13, these slats being disposed upon the outside of the corner posts, and the lowermost slat engages with the inner 80 face of the corresponding cleat on that end when the corner posts 12 are in a vertical position. The corner posts 12 are hinged to the bottom by means of hinges 14 which are engaged with those faces of the corner posts remote from the transverse cleats 11 so that the corner posts 12 move downward and inward 85 toward each other and into contact with the upper face of the floor 10 or bottom when the ends are turned down into collapsed position.

The sides are formed of horizontal rails 15 which are connected at their ends to the corner posts 16, and these corner posts 16 are disposed just directly inside of the corner 95 post 12 and are hinged by hinges 17 to the bottom of the box or crate so that the sides and, of course, the corner posts with them will turn downward against the box in a plane at right angles to the plane of movement of 100 the ends of the box or crate. It will be noted from Figure 3 that the hinges 17 are so disposed that when these corner posts 16 are turned down against the bottom 10 that the butt ends of these corner posts are out of 105 line with the corner posts 12 so that these corner posts in turn may be turned down upon the bottom 10. It is also to be noted that the corner posts 16 have less thickness than the corner posts 12 so that the slats 13 bear 110

against the slats 15 when the sides are turned downward against the bottom and the slats 13 are turned downward against the slats 15, in other words when the parts take the collapsed position shown in Figure 6.

I do not wish to be limited to any particular form of hinges 14 and 17, but preferably these hinges are put on with bolts 18 and preferably these bolts 18 pass down through the bottom and are engaged on their under sides with washers 19, illustrated as angular in form and through which the bolts pass, these washers being bolted, screwed, nailed or otherwise attached to the bottom of the box. Preferably the longitudinal slats of the sides 15 are reinforced by transverse braces 20 which may be of relatively light construction. This is to prevent these transverse slats from sagging. The top is formed by end pieces 21 and longitudinal pieces 22, these end pieces being wider than the longitudinal pieces 22 so as to project above the longitudinal pieces.

Attached to the longitudinal pieces and extending longitudinally of the crate are the slats 23, these slats being attached to the outside of the longitudinal pieces and being braced at their middle by two transverse spaced braces 24. An opening 25 is left in the center of the cover, and hinged to one wall of this opening is a trap 26, this trap being normally held down by means of any suitable latch or bolt 27. Of course, under some circumstances or in some forms of crates there is no necessity of a trap or door of this character, but in poultry crates and the like a door of this character is necessary.

It is to be noted in Figure 2 that the braces 24 do not extend into engagement or contact with the longitudinal side bars but terminate short of these side bars a distance equal to the thickness of the longitudinal slats of the side walls 15. Thus it will be seen that when the side walls 15 are vertically disposed and the cover is in place that the ends of the cross braces 24 will bear against these side walls and will hold the side walls from any inward movement, thus locking the side walls in their vertical position and, of course, the side walls in turn lock the end walls from any inward movement and thus the crate is locked against collapse. In addition to this, obviously bolts or other latches might be used for the purpose of holding these side walls in vertical position and the sides in squared relation. When the side walls are turned down upon the bottom and the end walls are turned down upon the side walls, as illustrated in Figure 6, the cover fits down over the butt ends of the side walls. Straps 28 or connections of any character are provided and these straps coat with buckles 29 upon the upper section so that when the top is brought down upon the folded lower section the straps pass through the buckles and

the whole structure is held then in very compact form for return shipment. These straps, as illustrated in Figure 1, also act to hold the top of the cover securely down upon the side frames when the latter are in erect position, and inasmuch as this cover when so disposed locks the sides from any movement and the sides lock the ends from any movement the crate is locked from collapse without the necessity of using sliding bolts, latches, screws or other locking means for this purpose.

The construction is very strong and at the same time simple, and it may be readily repaired because the slats are all upon the exterior of the frame and, therefore, may be readily taken off and replaced even in transit. A poultry crate will be ordinarily about twelve inches high but when folded it will only have a height of three inches, and while I do not wish to be limited to any actual dimensions, it will be obvious that, broadly speaking, the crate will have to be twice as wide as it is high. Of course, this crate can be made with partitions for the carriage of eggs, produce, etc., and these partitions may be taken out and put beneath the sides 15 when the latter are turned down. Thus these partitions will not add anything to the thickness of the folded crate. Preferably corner irons will be disposed on the top of the crate at each corner. As the crate has horizontal slats with heavy corner posts, the crate is particularly substantial and will last a relatively long time against the shocks, jars and other accidents of travel.

While I have illustrated and preferably use a crate formed with longitudinal slats, it will be understood that the side and end walls and top of the crate might be of solid wood, and the crate in this case having more the form of a box. I do not wish to be limited, therefore, to the use of these slats.

I claim:

A crate of the character described comprising a bottom, end walls and side walls, each including corner posts, the corner posts of the end walls being hinged to the bottom whereby to permit the end walls to be turned downward and inward toward the bottom, the corner posts of the side walls being disposed in the same plane as the corner posts of the end walls when the side walls are in a vertical position but the corner posts of the side walls being hinged inward of the corner posts of the end walls whereby the end walls straddle the folded side walls when the end walls are folded down upon the side walls, a cover comprising a rectangular frame, slats attached to the frame, the frame extending downward from the slats whereby to engage against the outer faces of the corner posts of the end walls when the corner posts of the end walls are turned into collapsed position, and transverse braces attached to the slats

and terminating short of the side members of the frame whereby to engage the upper margins of the side walls between the ends of the transverse members and the frame 5 when the side walls are in raised position, the top or cover and the bottom being provided with coacting straps and buckles for

connecting the top to the bottom when the parts are in collapsed condition and for holding the top in position upon the side walls 10 when the side walls are in erect position.

In testimony whereof I hereunto affix my signature.

KENT KANE McENTYRE.
